QUARTZ TUBE LAMP

Chester H. Braselton, New York, N. Y., assignor
to Sirian Lamp Company, Newark, N. J., a cor-
poration of Delaware

Application October 21, 1930, Serial No. 490,125

2 Claims. (Cl. 176—1)

This invention relates to an improved form of lamp or electric radiator in which energy emission from a solid emitter is combined with radiation from a gas surrounding the emitter.

5 One of the objects of the present invention is to provide a lamp of the above mentioned type in which the gas discharge adjacent the conductor is confined by means of a transparent solid substance. Another object of the invention is to pro-
10 vide a shield for electronic emission in a gas which resists high temperatures and electrical conductivity at said high temperatures.

Another object of the invention is to modify the type of emission of the combination solid and 15 gaseous conductor by the utilization of a shield of special material.

Further objects relating to general improvements in this type of radiator and improvements in various details and specific features of the in-
20 vention, together with improvements in the method of manufacture of the same will become apparent on consideration of the following speci-
fication and of the accompanying drawing, in which

25 Fig. 1 is a view in elevation of a modification of the invention, which may be preferred; and

Fig. 2 is a detail showing an enlargement of a portion of the conductor emitter.

In my co-pending application, Serial No. 30 459,048, filed June 3, 1930, I have described a type of lamp or energy emitter in which a conductor is coated with a substance which emits electrons profusely when heated. This coated conductor is immersed in an inert gas, such as argon, neon, or mixtures of the same, and with or without the 35 addition of various metallic vapors, such as that of caesium, and the whole placed in a container. When the coating is heated by means of the conductor, an ionized vapor of gases forms about 40 the conductor, which, together with the heated conductor, is a source of visible and invisible radia-
diation.

The type of lamp hereinabove mentioned and disclosed in said co-pending application, is utilized 45 in the present invention. I enclose in an envelope 10, which may be of glass or other transparent material, a support 11, which is also of glass, and it is sealed to the container. Mounted on the support 11 are standards 12, 13 and 14, of 50 suitable metal, such as nickel. These standards extend through the stem or support 11 to points external to the bulb so that appropriate electric potential may be applied thereto. The standard 12 has an L-shaped bend 15, and connected be-
55 tween the end 16 of this bend and the upper end

17 of the standard 13 is a coil of tungsten wire 18, which has a diameter of approximately .08". This wire, for a portion of its length, has a coating 19 of electron emitting material. This material is applied to the conductor in the following manner, as described in the co-pending application hereinabove mentioned.

5 In accordance with said application, a filament of appropriate resistance, such, for example, as 150 ohms, is placed in heating relationship with 10 various alkaline earth metal oxides, such as the oxides of barium, strontium, calcium or other materials which have been found to emit electrons densely when heated. The base filament is tungsten or tantalum wire, although other metal 15 conductors may be used. It is not necessary, ordi-
narily, that the base material be highly refrac-
tory, as the operating temperatures may be rela-
tively low, in many cases not being above that of 20 low red heat.

The filament is preferably coiled and the oxides either applied as a paste to the exterior of the coil, or as a core or rod to the coil interior. The oxide material initially may be in the proportions of 40 grams of barium carbonate, 40 grams 25 of calcium carbonate, 8 grams of barium nitrate with a binder of sufficient nitrocellulose dissolved in amyl acetate to hold the coating on the wire. The filament is then mounted on a stem sup-
port and sealed in the bulb of the envelope.

30 The exhaust pump is then connected to the bulb and an oven lowered thereupon to raise the temperature of the bulb and contents to about 400° C., or to as high a temperature as the envelope will stand without softening. Simultane- 35ously, electric current is passed through the fila-
ment, which is heated to red heat of approxi-
mately 600° C. The heat and exhausting pro-
cess is continued until there is no fluorescence 40 when the high tension current is directed against the wall of the bulb, or in other words, until there is practically no more gas inside of the bulb. A vacuum of about one-half of a micron is an ap-
proximate limiting value.

The current is then increased through the fila-
ment so that the temperature thereof is slowly 45 raised until it is about 800 degrees, or a bright red color, the exhaust operation being continued until the newly emitted gases are removed. The oven is then raised from the bulb and the fila-
ment heated to about 1200° C., the pumping being 50 continued until a high vacuum of one-half mi-
cron is again obtained.

The pump is then shut off and the current 55 tuned off, thus completing the process. Where

a more complete amalgamation of the coating is desired, about one-half mm. of neon gas is admitted to the bulb. The filament current is then turned on and gradually increased until a diffused glow completely fills the bulb. When the discharge is uniform throughout the bulb, the filament current is turned off and the pump applied to remove the neon gas. The filament temperature is then raised for a short interval to about 1400° C., with the pump operating to remove any undesirable gases which may have been thrown off during the activation process. Should white discharge spots appear on the filament or support rods, it is an indication that the gases or vapors within the bulb have not been completely removed, and the bulb is again exhausted and the whole process of activation repeated.

With the actuation process satisfactorily completed, the filament circuit is disconnected and the pump turned off and the appropriate amount of gas admitted to the bulb. In one form of my invention I utilize neon and argon gases in the relative amounts of 50 mm. of neon gas, and 150 mm. of argon. Other monatomic gases, such as krypton and helium or metal vapors such as those of mercury, caesium and rubidium may also be used. The bulb is then sealed off and a small quantity of magnesium flashed to absorb additionally impurities, thus completing the process.

Chemically pure gases are desirable.

The standard 14 is extended parallel to the conductor 18 and has welded thereto supporting cross bars 20 and 21 which terminate in coils 22 and 23, these latter serving to support a tube of quartz 24. The tube 24 encloses the coated sections of the conductor 18.

Surrounding the standard 12 is a tube 25 of glass or similar insulating material, which serves to prevent short-circuiting between this standard 40 and the associated standard 17 and conductor 18.

When appropriate inert gases are included within the container 10, such, for example, as the combination of neon and argon in the proportions of 50 mm. of neon and 150 mm. of argon, 45 together with a small percentage of the vapors of caesium or mercury, and an electric tension applied to the standards 12 and 13 through the external lead-in wires, the conductor 18 becomes heated together with its coating 19, and a layer 50 of ionized gases forms adjacent the coated conductor. This ionized layer is within the quartz tube. The purpose of the quartz tubing is now apparent in that it serves to confine the activated gaseous layer adjacent the conductor. An active 55 gaseous emanation of this type tends to spread out and become diffused, so that the luminosity and energy per unit volume is materially diminished. The quartz tube confines emanation by reason of its physical dimensions and because 60 its resistance to electric current flow is not affected by the electronic and ionic bombardment, and hence, it is not disintegrated by the high temperatures, nor does it become conductive. Moreover, because of its transparency, where the 65 device is intended for visible radiation, radiation is not prevented.

It is important that the inner diameter of the quartz tube be appropriately determined so as not to cause deposition of particles of the conductor or its coating. This seems to be in part a function of the temperature of the quartz tubing, and it is preferable that the mass of the tube should not be too large per unit length so as to exercise too great a lagging effect on the temperature conditions within the bulb 10. Quartz

has been mentioned as a satisfactory material for this purpose, although various other material having equivalent properties may also be used. A visible radiation requires that the tubing 24 be transparent to light, but the radiator is, of course, 5 usable for other purposes, such as the securing of infra-red or ultra-violet radiation, in which case it is not requisite that the tubing be transparent to visible radiation.

As suggested above, the light is intended for 10 use as a radiator, and there is no intent to confine the radiation to the visible range, although the modification as shown depends primarily for visible radiation in conjunction with a quartz tubing.

A light emission secured by this device, in conjunction with the quartz tubing, is very bright and brilliant. The light energy primarily is derived from the conductor and coating and the layer or ionized gases adjacent the tube within 20 the tubing. However, a portion of the energy radiation comes from the tube itself, and by suitable dimensioning of the tube, more or less of the radiation may be concentrated in the quartz tube itself.

The filament has been described as coated with a coating material 19, for the purpose of augmenting the electron emission of the conductor and thereby to cause ionization of the adjacent gases. However, instead of the coating, the material of the coating may be mixed in with the conductor material so that a homogeneous mixture exists without any external coating, and will function in a manner similar to the coated conductor. For example, I may employ thoriated 30 tungsten; that is, tungsten which includes a mixture of tungsten, thorium or thorium oxide, obtained by chemically combining thorium nitrate with tungstic acid. The presence of the thorium oxide throughout the tungsten mass of the conductor brings about the increase of ionization 35 desirable for this type of lamp.

Mention should be made also of the desirability of including a small amount of calcium with the caesium vapor introduced by means of pellets of 45 metals which are subsequently vaporized by electro-magnetic means. The presence of the calcium with the caesium vapor, either as such, or as a deposit on the conductor, tends to increase the efficiency of the lamp.

The various elements of the lamp as hereinabove mentioned define an operative construction. However, certain structural modifications may be made which adapt the lamp for specific uses or increase its operativeness under certain 55 conditions. For instance, due to electrical surge effects or high temperatures, arising from other causes, the tungsten coil adjacent its point of connection with the supports may tend to fracture. To overcome this difficulty the wire at this 60 point may be made thicker, or an additional alternative conducting path may be provided, as shown in Fig. 2.

This conductor may terminate in a coil 26 surrounding the primary coil and thus supply an enlarged conducting path for excess current, and in this way prevent fracture. Various other means for preventing fracture may be utilized.

The use of a coiled wire has been detailed in connection with this lamp. I have found also, 70 however, that a straight coated wire will accomplish the same results and is preferable in certain arrangements. I have also found that where a limited amount of coating material is desirable, it may be applied in the form of an elongated 75

core having an angular cross-section, such as that of a triangle. This form, for instance, gives contact at two or possibly three points on the interior of the coil, providing a much lesser amount of ionized material than if the whole interior were coated with the same.

Note should be made that both the standards 13 and 14 may be encased in an insulator tube, such as a glass tube 25, as applied to the standard 12. Other insulating materials, such as coated compounds, may be applied to the standards instead of the glass tubes. A further feature of the invention to which attention should be directed is that the ionization of the coating tends 15 to prevent vaporization of the tungsten, and hence the lamp may be operated at higher temperatures without blackening the interior of the bulb. This is very advantageous for lamps intended primarily for illumination.

Attention should be directed to the fact that the halo or layer of active gases may be varied in thickness by variation in the pressure of the gas. A low pressure tends to diffuse and enlarge the halo, while a high pressure tends to 25 confine the halo to the immediate surface of the electron emitting substance. Consequently, in the commercial design of radiating devices, such as the type described, there should be a correlation between the diameter of the interior 30 of the quartz tube and the pressure of the gas so that there will not be a sufficient diffusion of the ionized gas layer beyond the diameter of the tube, as this may result possibly in decrease in efficiency and also in discoloration of the tube 35 interior. This application is a modification of the invention shown in my co-pending application Serial No. 478,050, filed August 27th, 1930.

Various structural details have been shown in this modification of the invention. These, of course, may be varied without departing from the scope of the invention as defined in the claims hereto appended.

I claim as my invention:

1. An energy radiating device comprising a container, a support therein, a single conductor within said container and mounted on said support, means to electrically connect both ends of 10 said conductor to points outside of said container, an electron emitting coating having an electron emissivity equal to that of the alkaline earth metal oxides on said conductor, and a tube of quartz surrounding a coated portion of said conductor and mounted on said support, and an atmosphere of ionizable gas within said container, 15 said gas having a breakdown potential per unit length less than that of the unit length of conductor necessary to raise the coating thereon to 20 electron emitting temperature.

2. An energy radiating device comprising a container, a support mounted therein, a single conductor mounted on said support, means to connect both ends of said single conductor to 25 points outside of said container, a coating of electron emitting material having an electron emissivity equal to that of the alkaline earth metal oxides on said conductor, a tube of transparent and heat resistant solid material enclosing the 30 coated portion of said conductor and mounted on said support, and an ionizable gas within the container, said gas having a breakdown potential per unit length less than that of the unit length of conductor necessary to raise the coating there- 35 on to electron emitting temperature.

CHESTER H. BRASELTON.
